F. W. MAZSICK

CABINET

Filed April 16, 1923

UNITED STATES PATENT OFFICE.

FRANK W. MAZSICK, OF NORTH MILWAUKEE, WISCONSIN.

CABINET.

Application filed April 16, 1923. Serial No. 632,341.

To all whom it may concern:

Be it known that I, FRANK W. MAZSICK, a citizen of the United States, and resident of North Milwaukee, in the county of Milwaukee and State of Wisconsin, have invented certain new and useful Improvements in Cabinets; and I do hereby declare that the following is a full, clear, and exact description thereof.

10 This invention relates to cabinets.

Objects of this invention are to provide a cabinet in which a shelf is provided, and is adapted to occupy a position either upon the inner side of the cabinet or upon the outer side thereof, and to provide such a shelf associated with a hingedly mounted door and adapted to occupy either a position upon the inner side of said door, or a position upon the outer side thereof and 20 at substantially right angles thereto.

Further objects are to provide a cabinet which is so constructed that the general ornamental appearance of the cabinet is not marred by the auxiliary shelf construction, to provide a cabinet in which articles may be removed therefrom and the door closed and may be rested upon the outwardly projecting shelf while the door is closed, and to provide a cabinet so constructed that the parts may be folded into inactive position and the door closed to thereby present substantially the conventional parts of the cabinet.

An embodiment of the invention is shown 35 in the accompanying drawings, in which:

Figure 1 is a fragmentary view of the lower portion of a cabinet with the shelf in its extended position.

Figure 2 is a sectional view on the line 40 2-2 of Figure 1.

Figure 3 is a sectional view on the line 3-3 of Figure 2, showing in full lines the position of the shelf when extended, and in dotted lines an intermediate position of the shelf, and a folded position thereof.

Figure 4 is a detail of one of the fittings employed in supporting the shelf.

The cabinet may comprise the usual body portion which includes a compartment or casing 1 and preferably a facing strip 2 associated therewith, as shown in the drawing. The inner portion of the body of the cabinet is preferably provided with adjustable shelves 3 of any desired type.

The cabinet includes a door 4 which in 55 the usual form is provided with a mirror 5 and is hinged to the body of the cabinet along a vertical edge, one of the hinges being shown at 6 in the drawings.

The lower portion of the door has two 60 notches cut inwardly from its lower edge within which fittings are mounted, such fittings being provided with rearwardly extending flanges 7 bent inwardly from a rear plate 8. This plate, as may be seen 65 from Figures 2 and 4, is provided with a bayonet slot having a vertical portion 9 and a horizontal portion 10. It is connected with a front plate 11 by means of a bottom member 12. The front member 70 11 is provided with a vertical bayonet slot which includes a vertical portion 13 and an inwardly and downwardly directed portion 14, the bottom portion 12 being provided with a slot, as shown in Figures 2, 75 3, and 4, which communicates with the slots 9 and 13. These plates 8 and 11 are adapted to be slightly inset within the bottom portion of the door and to grip a portion of the door between them. They are 80 secured in position by means of screws 15 countersunk within the plate 11 and threaded through plate 8, as shown in Figure 3, thereby firmly securing the fittings in position. As shown in Figures 1 and 2, two 85 of these fittings are preferably provided, and each carries a pintle pin 16 between the ears 7.

The shelf 17 has rigidly attached thereto a pair of members 18 which extend rearwardly therefrom and are provided with rounded or rod-like portions 19 terminating in hubs 20 revolvably and slidably mounted upon the pintle pins 16.

From the construction thus far outlined, 95 it is apparent that the shelf may occupy either a position upon the inner side of the cabinet and may extend vertically, as indicated in dotted lines in Figure 3, or when the door is open, may be rocked downwardly and outwardly, the rod-like portions 19 passing through the slots 9 and 13 and again upwardly through said slots as the shelf is rocked into a position externally of the door. When in this position the shelf is 100 slightly elevated, as shown in dotted lines in Figure 3, and is slid bodily sidewise so as to pass the rod portions 19 into the por-

- tions 10 and 14 of the fittings. The shelf is then lowered into the full line position shown in Figure 3 and is firmly held in this position by cooperation of the rod portions 5 19 and the depressed portions 14 of the slots in the forward plates. The door may now be closed and the shelf will be held in its outwardly projecting and extending position and is ready to support articles thereon.
- 10 When the shelf is in its inward position, it may be conveniently retained in its vertical or stored position by means of a spring clip 21 carried by the inner face of the door, as shown in Figure 3.
- 15 The invention is shown in its preferred form, but it is obvious that the cutout portions may be formed in the body part of the cabinet rather than in the door to permit the passage of the shelf supporting means 20 from its inner to its outer position.
- This type of cabinet will be found very useful. It frequently happens, for instance, that in shaving, when it is attempted to use the usual cabinet, that the shaving articles 25 have to be removed therefrom and thereafter the door must be closed in order to allow the mirror to be used. There is then no place to deposit the shaving articles. However, with the type of cabinet forming the subject 30 matter of this invention, a readily positioned shelf is provided and these articles may be deposited upon such shelf while in no way interfering with the free use of the mirror, and as will be appreciated, of course, this is 35 only one of the many uses to which this cabinet may be put.
- Although one specific form of the invention has been described in considerable detail, it is to be understood that the invention 40 may be variously embodied and is, therefore, to be limited only as claimed.

I claim:—

1. A cabinet including a door hinged to the body portion of the cabinet adjacent one edge, a shelf, and means rigid with said shelf and projecting therefrom and hinged to said door adjacent its bottom edge, whereby said shelf is adapted to stand vertically upon the inner side of said door or to project from the outer side of said door at substantially right angles thereto. 45
2. The combination of a cabinet including a body portion and a door hingedly mounted thereon adjacent a vertical edge, a shelf adapted to occupy a vertical position upon the inner side of said door or to project outwardly therefrom at right angles, fittings secured to the lower portion of said door and carrying pintle pins, and means rigidly attached to said shelf and slidably and revolvably mounted upon said pintle pin, said fittings having slots provided with vertical and transverse portions through which said rigidly attached means may be passed. 55
3. The combination of a cabinet including a body portion and a door hingedly joined thereto along a vertical edge, of a shelf hinged to said door adjacent the bottom thereof and adapted to be positioned vertically and upon the inner side of said door, or to extend outwardly therefrom at right angles, said door having cut-outs adapted to admit swinging motion of said shelf from its inner to its outer positions, and means for retaining said shelf in its vertical inner 70 position. 65
- 75

In testimony that I claim the foregoing I have hereunto set my hand at North Milwaukee, in the county of Milwaukee and State of Wisconsin.

FRANK W. MAZSICK.
